UNITED STATES PATENT OFFICE.

RICHARD M. GARRETT, OF YONKERS, NEW YORK, ASSIGNOR TO NESTLE'S FOOD COMPANY, OF NEW YORK, N. Y., A CORPORATION OF NEW YORK.

BOX-SEALING MACHINE.

Application filed July 7, 1922. Serial No. 573,378.

To all whom it may concern:

Be it known that I, RICHARD M. GARRETT, a citizen of the United States, residing at Yonkers, in the county of Westchester and State of New York, have invented certain new and useful Improvements in Box-Sealing Machines; and I do hereby declare the following to be a full, clear, and exact description of the invention, such as will enable others skilled in the art to which it appertains to make and use the same.

My invention consists in certain new and useful improvements in box sealing machines, and has for its object to provide a machine of this kind which will insure the flaps of a box being glued snugly together, obviating any separation of the meeting edges of the bottom of the box.

Another object of my invention is to provide a machine which will do away with the necessity of manual effort in pushing the flaps of a box together.

Heretofore in using a box pasting machine, it has been necessary for the operator to push the flaps inwardly with his fingers, and before the two platens came together to seal the box, he had to withdraw his hands to keep them from being injured. This allowed the flaps to spring back, and left a crack in the bottom of the box, when the sealing operation was completed.

With my improved construction it is not necessary for the operator to use his fingers in contracting the flaps of the box, as the top platen is provided with pivotally mounted spring actuated fingers and crowding arms which, as the top platen comes down, press the flaps together.

With the above and other objects in view which will appear as the description proceeds, the invention consists in the novel features herein set forth, illustrated in the accompanying drawings and more particularly pointed out in the appended claims.

In the drawings, numerals of like character designate similar parts through the several views.

Fig. 1 is an end view of my device showing the pivotally mounted fingers.

Fig. 2 is a side elevation with a portion of the frame cut away, showing the crowding arms.

Fig. 3 is a plan view of the device showing the two sets of fingers and crowding arms.

Figs. 4 and 5 are detail views of the top platen.

1 represents the frame, which is adapted to be secured to the floor, and which supports the working parts of my machine. This 60 frame is provided with bearings 2 for the arm 3 of the pivotally mounted lower platen 4. Secured to the lower portion of the arm 3, is a bumper 5 which registers with the stop 6, and regulates the radial movement of 65 the platen 4, as shown in Fig. 2, when a box is to be placed thereon. In order to insure the firmness of the machine, I provide a brace 7 which is secured to the frame work 1 at the upper end, and to the floor at the 70 lower end.

At the upper end of the frame 1, I provide a platen 8, which is secured to one end of a plunger 9, said plunger being slidably mounted in a bearing 10, and being rounded 75 at its upper end. At the extreme upper end of the frame 1, I provide another bearing 11, in which is pivotally mounted a cam lever 12, which engages the rounded end of the plunger 9, and by means of which the 80 platen 8 may be forced downwardly.

This top platen 8 is provided on its upper side with two sets of pivotally mounted fingers 13, which rock in the bearings 14 and the inner ends of which project downwardly through apertures 15 in the platen, said inner ends being provided with gripping means 16 for the flaps of a box to be sealed. These gripping means may consist of rubber, felt, or roughened metal surfaces, 85 or other suitable material.

To the outer ends of these fingers are secured crowding arms 17 which are in the form of strips extending lengthwise of the platen and which when the top platen comes 95 down, are forced inwardly toward one another, crowding the flaps of the box snugly together for sealing.

These arms 17 are secured to the fingers 13 by means of nuts and bolts 18 and are provided with springs 19 which allow them to possess a slight resiliency.

The fingers 13 are held in operative position by means of springs 20, which extend from the frame 1, and can be readily adjusted to give any desired movement required to force the flaps of the box together.

The operation of my device is obvious. The box is placed in an inverted position on the forming platen 4, which is in the position 110

shown in dotted lines in Fig. 2. The platen and box thereon are then moved into the position shown in full lines in Fig. 2 ready to be sealed, the glue having been applied to 5 the flaps where required. The platen 8 is then forced down by means of the cam lever 12, pushing the flaps of the box down as it goes.

As this platen 8 nears the bottom platen 10 4, the fingers 13 are brought into action, pushing the box flaps downwardly and inwardly at the same time. When the two platens are almost in contact with each other, the crowding arms 17 are brought 15 into action by the fingers 13 rocking on their pivots, and crowd the flaps of the box together.

It will be readily seen that there is no 20 danger of the crowding actions causing the flaps of the box to telescope or overlap, as the fingers 13 are snug against the flaps of the box, holding them down against the bottom platen 4.

When the cam lever 12 is released the 25 springs 20^a raise the platen 8 to its normal position.

From the foregoing it is believed that the 30 invention may be fully understood without further description and it is obvious that numerous changes may be made in the 35 details of construction, without departing from the spirit of the invention as expressed in the claims.

What I claim and desire to secure by Letters Patent is:—

1. A box sealing machine comprising a pair of platens, means for forcing one of said platens towards the other, and rigid means pivotally mounted on one of said platens 40 for crowding the flaps of a box together to insure a tight joint.

2. A box sealing machine including a pair of platens, means for moving one of said platens toward the other, and pivotally mounted rigid means associated with one of said platens for forcing the flaps of a box to-

gether when one of said platens is moved toward the other platen.

3. A box sealing machine comprising a pair of platens, means for moving one of said platens toward the other, and rigid fingers pivotally mounted on one of said platens and provided with crowding arms adapted to force the opposite sides of a box toward one another when said fingers engage the box flaps in the movement of the movable platen toward the other platen. 55

4. A box sealing machine as claimed in claim 3, in which the fingers and crowding arms are held in operative position by means of springs. 60

5. A box sealing machine as claimed in claim 3, in which the fingers are provided on their inner ends with gripping means.

6. A box sealing machine as claimed in claim 3, in which the crowding arms consist of elongated strips secured to the outer ends of said fingers. 65

7. A box sealing machine including a pair of platens, means for moving one of said platens toward the other, fingers pivotally mounted on the movable platen and having gripping ends extending beyond the face of the movable platen which is opposite to the surface of the other platen, and crowding arms operatively connected with said fingers and adapted to be actuated by said fingers for crowding opposite sides of a box, arranged on one of the platens, toward one another. 70

8. A box sealing machine including a pair of platens, means for moving one of said platens toward the other, fingers movably connected to one of said platens and adapted to operate when the movable platen is moved toward the other platen for causing the flaps of a box to move toward one another, and means actuated by said fingers for forcing the opposite sides of the box toward one another while the flaps are being laid. 85

In testimony whereof I affix my signature.

RICHARD M. GARRETT.
